UNITED STATES PATENT OFFICE

REX W. MANEVAL, OF FRANKFORT, KANSAS

VENTILATION-CONTROLLING MEANS FOR CHICKEN BROODERS

Application filed December 15, 1927. Serial No. 240,232.

My invention relates to a ventilation controlling means for chicken brooders.

The object of my invention is to provide a ventilation system for chicken brooders controlled by a thermostat.

A further object of my invention is to provide a chicken brooder having a plurality of compartments simultaneously heated, and each compartment separately controlled by a 10 thermostat.

A still further object of my invention is to provide a heating system that will extend to a plurality of brooders or units of brooders.

A still further object of my invention is to 15 provide a chicken brooder having a single air shaft intermediately positioned to a plurality of compartments.

A still further object of my invention is to 20 provide a moisture pan, by which means the compartments are supplied with moisture and heat simultaneously.

These and other objects will be hereinafter more fully explained.

Referring to the drawings:

Fig. 1 is an elevation of a series of brooders partly in section for convenience of illustration.

Fig. 2 is a plan view of one unit and a fragmentary portion of an adjacent unit, parts 25 moved for convenience of illustration.

Fig. 3 is an enlarged sectional view illustrating the steam pipes, moisture pan, thermostat, and the direction of the circulation.

Fig. 4 is an enlarged longitudinal view 30 through the duct between the units.

In the following description like characters will apply to like parts throughout the different views.

The mechanism herein disclosed consists 35 of an air shaft 1 positioned between a pair of brooders 2, the said brooders comprising a plurality of compartments placed above each other and designated as A, B, C, D, and E; other compartments may be added. The

40 brooders may be of any standard make, but modified so that my ventilating system may be installed. The said system consists of an enclosed air shaft 1 positioned transversely of a pair of brooders 2, one being on each side as 45 shown in Figs 1 and 2; the ends of the brood-

ers adjacent the shaft are closed by hingedly connected doors 3; the said doors are of solid construction, so that when closed the heat will not pass therethrough, and are hinged to a ceiling 4 which is spaced from a wire screen 55 floor 5, the said floor having positioned thereunder a removable pan 6 as a catchall and cleaning means for their respective compartments. A similar screening 5' will extend over the door openings to prevent the chicks from falling into the shaft, the said screen being on the inside of the doors and to cover the entire area thereof.

Positioned rearwardly of the ceiling 4 is a fabric partition member 7 extending downward so that the lower edge thereof is well spaced from the said ceiling, but leaving sufficient room for small chicks to pass between the lower edge and the floor of its respective compartment, the fabric partition functioning as a baffle and causing the heat entering the doors as indicated by the arrows in Figs. 1 and 3 to pass upward and outward through the rear portion of the compartment; and being so arranged, the fabric partition also 70 forms a pocket in which the thermostat 8 is positioned. The said thermostat is axially positioned with the rods 9 and 9', the ends of which are connected to the sides of the thermostat. The rod 9' is adjustably connected to 75 the lower end of an arm 7' through the medium of a nut 10 and a wing nut 11 threaded 80 engaging thereon, the opposite end of shaft 9 pivotally engaging with the door as at 12, whereby the said door is opened and closed by 85 the thermostat.

As a means to counterbalance the outward swing of the door, a spring 13 is attached to the ceiling 4 and to the top of the door above the hinge 14. Longitudinally positioned in a 90 duct 15 at the lower end of shaft 1 are heating coils 16, the said coils being supplied with steam from a plant arranged therefor, but not shown in the drawings.

Above the coils and in close proximity thereto is a pan 17 in which is placed a quantity of water which is gradually evaporated by the heating coils and circulated through the different compartments for the chickens.

As a supporting means for the coils are 100

bars 18 extending to and connecting with the walls 18', the said walls being the carrying means for the intermediate portion of the brooders. It will be understood that an opening 5 will be arranged beneath each wall as shown at 19, the said opening extending approximately the full width of the doors in each compartment through which the fresh air will pass into the shaft. The pan is supported on brackets 20 having their bearings 10 on the said bars 18, as shown in Figs. 1 and 3.

That portion of the compartments adjacent the shaft 1 is enclosed solidly. That is to say, the doors 21 may be paneled with wired glass 15 or other transparent substance. The partition between the said compartments as at 22 is likewise solid, by which means a heating chamber is formed, the heat therefrom dispensing through the rear portion which is enclosed 20 at the sides and rear end with screen wire. The top of each compartment is sealed by a removable pan 23 slidably engaging guides similar to those shown at 6' in Fig. 3. It will be understood that my invention does 25 not claim broadly the screened compartments or the removable pans, as brooders have heretofore been made similar to the construction shown.

As heretofore stated, units may be connected as shown in Fig. 2, and when so arranged the duct extends from one unit to the other as shown by the enlarged section in Fig. 4, the said duct having a cover 24 and a ceiling 25 extending downward to the center so that 30 the heat from the coils will readily flow each way as shown by the arrows in said figure, by which means the accumulation of the heated air will dispense freely to the adjacent shafts.

While I have not shown the thermostat arrangement in all of the compartments, it will be understood that there will be one to each thereof, as detailed in Fig. 3.

Such modifications may be employed as lie 45 within the scope of the appended claims.

45 What I claim as new and desire to secure by Letters Patent is:

1. In a ventilation controlling means for chicken brooders, in combination with brooders of the kind described comprising a plurality 50 of compartments, hingedly connected doors on the upper sides of each of the compartments and sides transversely positioned to the doors, whereby a circulating shaft is formed, a heating element and a moisture element at the base of the shaft, a duct in 55 which said elements are positioned and means for introducing air to the duct, a fabric partition across each of the compartments spaced a short distance from the doors, and a thermo- 60 stat supported by an arm and the upper side of the doors as opening and closing means therefor to control the temperature within the compartments.

2. In a ventilation controlling means for 65 chicken brooders, a brooder of the kind

shown and described, comprising a plurality of compartments and units, a fabric partition downwardly extending from the ceiling of each compartment, the lower edge of which is spaced from the floor of its respective compartment, a ceiling spaced from the floor of the compartment above, said ceiling extending from the partition to one end of the compartment, a door hingedly connected to the ceiling so that the said door will close the end of the compartment and the outer end of the space between the ceiling and the floor of the above compartment, a spring connected to the upper edge of the door, and a thermostat connecting the upper edge of the door with an arm adjacent the fabric partition, the spring to open the door when the thermostat recedes or contracts, a circulating air shaft in which the doors will swing, a heating coil and water container at the lower end of the shaft, as circulating means through the compartments, substantially as shown.

3. In a ventilation controlling means for chicken brooders, brooders of the kind described, said brooders spaced apart, a duct extending from one brooder to the adjacent brooder connecting the same, a cover for the duct between the brooders comprising a level portion and a V-shaped member, the center of which downwardly extends as discharging means for the accumulated heat therein to the vent shaft of each of the adjacent brooders, substantially as shown.

In testimony whereof I affix my signature. 100
REX W. MANEVAL.
